UNITED STATES PATENT OFFICE

ERNEST F. BONSER, OF LEICESTER, ENGLAND, ASSIGNOR TO UNITED SHOE MACHINERY CORPORATION, OF PATERSON, NEW JERSEY, A CORPORATION OF NEW JERSEY

PATTERN COPYING MACHINE

Application filed September 23, 1929, Serial No. 394,701, and in Great Britain October 9, 1928.

This invention relates to pattern copying machines and is illustrated as embodied in a lathe for turning shoe lasts of the type shown in United States Letters Patent No. 1,293,276, granted February 4, 1919, on application of L. B. Whipple.

Such machines are ordinarily provided with a pendulum-like swing frame, at the lower end of which are rotatably mounted a model and a work block, end to end. Two carriages, bearing a model wheel and a cutter, respectively, are driven along the main frame parallel to the plane of the swing frame, and beside the model and block, which rotate in contact with the model wheel and cutter. The irregularities in the shape of the model cause the swing frame to oscillate, as the model rotates, thus determining the varying depth to which the cutter cuts different parts of the block.

The swing frame is 40 or 50 inches square, is heavy, and has a considerable moment of inertia. Unless the model and block are rotated relatively slowly there is considerable jar as the model wheel rolls down from a high place on the model, such as the cone, into the hollow in the model below the cone. This often causes the swing frame to be distorted, and consequently the cutter cuts too deeply into the block at the corresponding point. This results in inaccurate work.

It is a principal object of this invention to avoid the difficulty referred to. Accordingly, a feature of the invention consists in a copying lathe having, as herein illustrated, shock absorbing means comprising co-operating parts respectively mounted on the swing frame and the cutter carriage to absorb the jar at the point where the distortion of the swing frame has its maximum extent. Preferably, in accordance with the invention, this shock absorbing means is in the form of a fluid check device which may be mounted either on the swing frame or on the cutter carriage, and contacts with a member on the cutter carriage or on the swing frame.

In accordance with another feature of the invention the illustrated contact member is shaped roughly to the contour of the model in the locality where the check is effective, so

that its mechanical effect will be more uniform from one end to the other of the last.

Fig. 1 is a side view of the machine;

Fig. 2 is an enlarged detail of the pneumatic check device; and

Fig. 3 is a detail of the contact cam.

The main frame 10, swing frame 12, and cutter carriage 14, with its cutter 16 are of ordinary construction. The swing frame 12 is shown in Fig. 1 broken away at its lower corner, opposite the cutter carriage, exposing its lower frame bar 18, on which the pneumatic check device 20 is mounted. The cutter carriage carries a bracket 22 on which the contact cam 24 is mounted. The arrangement of the check device and the cam may be reversed if desired.

The details of the check device and the cam are shown in Figs. 2 and 3. The check device is adjustably mounted on a bracket 26, fastened to the bar 18, by bolts and slots at 28, 30.

The pneumatic check itself comprises a cylinder 32 mounted on the swing frame 12 so that its axis is substantially horizontal and perpendicular to the work and model axes, indicated at 33, Fig. 1. Inside the cylinder is a piston 34 having a stempiece 36 projecting through one end of the cylinder towards the cutter carriage 14. Projecting internally of the cylinder, from a cover 38 mounted on the opposite end thereof, is a rod 40 on which is carried a coiled spring 42 passing axially through the piston and extending into a recess 44 bored in its stempiece 36. The spring 42 thus tends to keep the piston towards that end of the cylinder nearest the cutter carriage 14.

In a boss 46 on the inside of the cylinder cover 38, at the base of the rod 40 is bored diametrically of the cylinder a passage 48 communicating with a second passage 50 bored axially through the cover 38 which in turn communicates with an outlet 52 passing radially to the outside of the cover. In the passage 50 is fitted a block 54, which may be set in position, by an adjusting screw 56 extending from the face of the cover, to regulate the amount of opening of the passage 52 through which air may be ejected from

the cylinder by the piston. The block 54 is preferably pressed up to the screw 56 by a spring 58 within the passage 50 and the screw 56 may be held so as to retain any setting given to it by a spring-pressed washer 60 against its side. In the end of the cylinder opposite to the cover there is an opening 62 permitting free ingress and egress of air, and in the end closed by the cover there is a ball valve 64 which admits air to the cylinder behind the piston when the latter moves to the left in Fig. 2.

The cam or abutment 24 with which the stempiece of the air check co-operates is shown as a metal plate (Fig. 3), mounted by bolts 65, passing through slots 66 in the plate, upon the bracket 22 so as to project approximately horizontally from the front side of the cutter carriage 14. The front edge of the plate shown (see Fig. 3) is cut to a special formation which corresponds in its effect to the shape of an average high coned last. The front edge of the plate has approximately midway of its length a short portion 68 parallel to the slideway of the cutter carriage, and corresponding to that part of the last where the cone is highest. At either side of the portion 68 the front edge of the plate 24 is sloped backwardly (away from the pneumatic check 20). At that end of the plate which traverses past the air check stempiece while the cutter carriage traverses past the forepart of a last being turned, the backward slope is preferably made in two stages, the first part 70 which corresponds with the instep portion of the last, being cut at a greater angle (to the line of that parallel portion) than the end portion 72, which corresponds to the toe portion of the last. The portion of the cam 24 corresponding to the heel end of the last may be sloped backwardly as shown at 74.

As a cam plate of the above formation traverses past the air check stempiece 36 (as the cutter travels along the workpiece) the effect is to bring the air check gradually into action, to retain the action at a maximum during the time when the greatest variations of radial measurement of a last (usually in the cone part) are occurring and then gradually to reduce the check action. It will be understood, however, that the checking action of the device occurs only during a portion or portions of each revolution of the model and workpiece when the swing frame has fallen in toward the model wheel and cutter. Following the passage in each revolution of a high portion of a model past the point of contact with the model wheel the portion of the swing frame which carries the workpiece moves toward the cutter carriage and with high steep coned lasts this movement may be very rapid, terminating with an equally sudden stoppage. The action of the pneumatic check at such time is to pre-

vent what amounts to overthrow of the workpiece toward the cutter by absorbing some of the momentum of the moving swing frame.

The amount of resistance given by the pneumatic check to movement of the swing frame toward the cutter carriage may be varied by changing the position of the block 54 in the outlet passage 50, and the smaller this outlet the greater becomes the checking action. Return movement of the piston within the cylinder during times when the swing frame is moving away from the cutter carriage is produced by the spring 42 mounted behind the piston 34 and the ball valve 64 admits air freely when the piston is thus returning.

Having described my invention, what I claim as new and desire to secure by Letters Patent of the United States is:

1. In a copying lathe, a main frame, a swing frame arranged to carry a model and a block, a model wheel carriage and a cutter carriage arranged to traverse along the main frame beside the swing frame, and shock absorbing means comprising co-operating parts respectively mounted on the swing frame and on one of the carriages.

2. In a copying lathe, a main frame, a swing frame arranged to carry a model and a block, a model wheel carriage and a cutter carriage arranged to traverse along the main frame beside the swing frame, and shock absorbing means comprising co-operating parts respectively mounted on the swing frame and on the cutter carriage.

3. In a copying lathe, a main frame, a swing frame arranged to carry a model and a block, a model wheel carriage and a cutter carriage arranged to traverse along the main frame beside the swing frame, and a fluid-operated check device and a contact member therefor, mounted one on the swing frame and one on one of the carriages.

4. In a copying lathe, a main frame, a swing frame arranged to carry a model and a block, a model wheel carriage and a cutter carriage arranged to traverse along the main frame beside the swing frame, and a fluid-operated check device mounted between one of the carriages and the swing frame.

5. In a copying lathe, a main frame, a swing frame arranged to carry a model and a block, a model wheel carriage and a cutter carriage arranged to traverse along the main frame beside the swing frame, and a fluid-operated check device and a contact member therefor, mounted one on the swing frame and one on the cutter carriage.

6. In a copying lathe, a main frame, a swing frame arranged to carry a model and a block, a model wheel carriage and a cutter carriage arranged to traverse along the main frame beside the swing frame, and a pneumatic check device and a contact member

therefor mounted one on the swing frame and one on the cutter carriage.

7. In a copying lathe, a main frame, a swing frame arranged to carry a model and a block, a model wheel carriage and a cutter carriage arranged to traverse along the main frame beside the swing frame, and a pneumatic check device having a projecting stem and a contact cam for the stem, mounted one on the swing frame and the other on one of the carriages.

8. In a copying lathe, a main frame, a swing frame arranged to carry a model and a block, a model wheel carriage and a cutter carriage arranged to traverse along the main frame beside the swing frame, and a pneumatic check device having a projecting stem and a contact cam for the stem, mounted one on the swing frame and the other on the cutter carriage.

9. In a copying lathe, a main frame, a swing frame arranged to carry a model and a block, a model wheel carriage and a cutter carriage arranged to traverse along the main frame beside the swing frame, and a shock absorbing device and a cam for co-operating therewith, mounted one on the swing frame and one on one of the carriages.

10. In a copying lathe, a main frame, a swing frame arranged to carry a model and a block, a model wheel carriage and a cutter carriage arranged to traverse along the main frame beside the swing frame, and a shock absorbing device and a cam for co-operating therewith, mounted one on the swing frame and one on one of the carriages, the cam being shaped to correspond with the upper portion of the model profile.

11. In a copying lathe, a main frame, a swing frame arranged to carry a model and a block, a model wheel carriage and a cutter carriage arranged to traverse along the main frame beside the swing frame, and a shock absorbing device mounted on the swing frame and a cam for co-operating therewith mounted on the cutter carriage.

In testimony whereof I have signed my name to this specification.

ERNEST FREDRICK BONSER.
